UNITED STATES PATENT OFFICE.

GODFREY NIEBEL, OF NEW YORK, N. Y.

DESIGN FOR AN ELECTRIC BULB.

Application filed November 2, 1927. Serial No. 23,971. Term of patent 14 years.

To all whom it may concern:

Be it known that I, GODFREY NIEBEL, a citizen of the United States, and resident of New York city, in the county of New York and State of New York, have invented a certain new, original, and ornamental Design for an Electric Bulb, of which the following is a specification, reference being had to the accompanying drawing, forming part thereof.

The view is an elevation of an electric bulb or similar article, showing my new design.

I claim:

The ornamental design for an electric bulb or similar article, substantially as shown.

Signed at New York, in the county of New York and State of New York, this thirty-first day of October, A. D. 1927.

GODFREY NIEBEL.
